G. A. ERRINGTON,
 CAR SWITCH OPERATING MECHANISM,
 APPLICATION FILED JUNE 15, 1914. RENEWED MAR. 29, 1915.
1,138,203. Patented May 4, 1915.

UNITED STATES PATENT OFFICE.

GEORGE ARTHUR ERRINGTON, OF TORONTO, ONTARIO, CANADA.

CAR-SWITCH-OPERATING MECHANISM.

1,138,203.

Specification of Letters Patent.

Patented May 4, 1915.

Application filed June 15, 1914, Serial No. 845,150. Renewed March 29, 1915. Serial No. 17,893.

To all whom it may concern:

Be it known that I, GEORGE ARTHUR ERRINGTON, of the city of Toronto, in the county of York, in the Province of Ontario, 5 Canada, have invented certain new and useful Improvements in Car-Switch-Operating Mechanisms, of which the following is the specification.

My invention relates to improvements in 10 car switch operating mechanisms as covered in a co-pending application Serial Number 845,149 bearing even date of filing and the object of the present invention is to devise means carried by the car for engaging the 15 tripping lever to operate the switch point and it consists essentially of a vertical casing carried by the car and having vertical guide ways, a spring held plunger held in such guide-ways adapted to be operated by 20 foot pressure, mechanisms for locking the plunger in the depressed position and means for automatically releasing the same after operating the switch tripping lever as hereinafter more particularly explained by the 25 following specification.

Figure 1, is a side elevation of a car vestibule showing my device in position therein. Fig. 2, is a vertical section through the operating mechanisms in the inoperative position. Fig. 3, is a similar view to Fig. 2 showing the device in the operative position. Fig. 4, is a side elevation of my operating mechanism. Fig. 5, is a plan view of a switch operated by my device and my device 35 in the position it assumes as it approaches the switch lever. Fig. 6, is a plan section on $x-y$ Fig. 2.

In the drawings like letters of reference indicate corresponding parts in each figure.

40 A is the car track.

B² is a branch line, and C is the switch point.

G³ is the tripping lever pivoted at G⁴ and designed to extend at one end into the tripping box I and to be operatively connected 45 at the other end to the switch point as described in my co-pending application hereinbefore referred to.

M is the ordinary controller casing of the 50 car.

M' is a vertical casing located in the car vestibule preferably in proximity to the controller casing M. The casing M' is provided with vertical guides M².

55 M³ is a vertically movable member slidably held in position by the guide ribs M².

of the casing. The member M³ is normally held in its upper position by the tension springs M⁴.

M⁵ is a notch formed in the member M³. 60

M⁶ is an orifice formed in the casing M'.

M⁷ is a vertical slot also formed in the casing M' beneath the orifice M⁶.

M¹⁷ is a locking lever provided with an inturned upper end M⁸ designed to fit into the notch M⁵ when in its locked position. The lower end of the locking lever M¹⁷ extends through a suitable slot in the car floor into proximity with the track.

M⁹ is an extension to the member M³, such 70 extension piece being secured in a cross recess M¹⁰ by set screws M¹¹ extending through the internally threaded orifices M¹² formed in the member M³ and through slots M¹³ formed in the extension piece M⁹. 75

M¹⁴ is a vertical slot formed in the casing M' and M¹⁵ is a tread plate secured to the member M³ and extending through the slot M¹⁴ for a purpose which will hereinafter appear. 80

O is a roller mounted on a vertical bearing carried by the extension M⁹ and designed to engage the tripping lever. O' is a roller also carried by the extension M⁹ on a horizontal bearing and designed to contact 85 with the ground when the member is depressed as it approaches the tripping box.

O³ is a cushioning spring designed to receive the plunger at the limit of its return movement. 90

Q is a spring cushioning block provided with a laterally extending pin Q' which projects into the tripping box I.

In operating my device when the car approaches the switch and it is desired to turn 95 the switch point the motorman places his foot upon the tread M¹⁵ forcing it downwardly carrying the depressible member M⁹ and roller O' thereof into contact with the ground. As soon as the roller O' reaches the 100 tripping box I it drops thereinto passing longitudinally of the same until the roller O contacts with the tripping lever G³. The tripping lever G³ is thereby thrown in the direction of arrow so as to operate the switch 105 described in my co-pending application hereinbefore referred to.

When the motorman depresses the member M⁹ it is locked in its depressed position by the projection M⁸ entering the recess M⁶, the projection M⁸ being 110 thrown thereinto by means of the spring 2 located in proximity to the lower end of the

locking lever M^17 . After the tripping lever has been thrown as above described the lower end of the locking lever strikes against the projection Q' , such projection slightly giving by means of the cushioning spring to take up the shock. By this operation the upper end of the locking lever formed by the projection M^8 is thrown out of engagement with the recess M^6 and the depressible member is carried upwardly again to its normal position by means of the springs M^4 striking against the cushioning spring O^3 at the upward limit of its stroke.

From this description it will be seen that I have devised a very simple device adapted to be carried by a car whereby an automatic switch operating mechanism having an operating tripping lever extending horizontally in proximity to the track may be operated and which will automatically release so as to return to its normal position when such operation has been completed.

What I claim as my invention is:

1. In a car switch operating mechanism, a tripping member designed to be carried by the car and comprising a casing located in the car vestibule and having a vertical slot in one side thereof and having an orifice located above the slot, a vertically movable spring held member adapted to engage, when depressed, the switch point operating lever extending horizontally in proximity to the track, a tread plate extending from the spring held member through the slot of the

casing, a locking lever pivotally supported in a suitable bracket carried by the depressible member and having an inturned upper end and a depending lower end adapted to engage a suitable projection lying in the path of the depressed end of the depressible member when the locking lever is carried by the depressible member to the depressed position, and spring means for forcing the lower end of the locking lever normally outwardly from the casing so that when the depressible member is depressed the upper inturned end of the locking lever will be forced through the orifice in the casing into engagement with the depressible member to hold the depressible member in the depressed position, as and for the purpose specified.

2. In a car switch operating mechanism, a tripping member designed to be carried by the car and comprising a casing located in the car vestibule, a vertically movable spring held member therein, means for depressing said spring held member, locking means adapted to hold the spring held member in the depressed position, means for releasing the spring held member from the depressed position and spring cushioning means designed to receive the depressible member when released at the end of its upward stroke, as and for the purpose specified.

GEORGE ARTHUR ERRINGTON.
